UNITED STATES PATENT OFFICE.

WILLIAM BRUCE KNAPP, OF NEW YORK, N. Y., ASSIGNOR TO CLAIR W. FAIRBANK, OF NEW YORK, N. Y.

DRINKING-FOUNTAIN.

1,187,747.

Specification of Letters Patent. Patented June 20, 1916.

Application filed May 11, 1911. Serial No. 626,618.

To all whom it may concern:

Be it known that I, WILLIAM BRUCE KNAPP, a citizen of the United States, and a resident of the city of New York, borough 5 of Manhattan, county and State of New York, have invented certain new and useful Improvements in Drinking-Fountains, of which the following is a full, clear, and exact description.

10 This invention relates to certain improvements in drinking fountains, of that type in which there is an upwardly directed nozzle, from which water may flow at a limited rate, and over which a person desiring a drink 15 may place his mouth. Fountains of this kind are commonly used in parks, schools and other public and semi-public places, an object being to dispense with the unsanitary public drinking cup. If the water be per- 20 mitted to flow continually at the fountain, there is an enormous waste of water, and if each person be permitted to turn the water on and off for himself, it has been found that certain persons, particularly children, 25 will place the lips in direct contact with the nozzle before turning on the water, which renders the fountain no more sanitary than the public drinking cup.

One main object of my invention is to 30 avoid these objections by permitting each individual to turn on the water for himself, but positively preventing him from placing his lips to the nozzle before the flow of water starts. In most drinking fountains, a 35 regulating device is provided for limiting the rate of flow of the water, and often mischievous persons will tamper with this regulating device so as to seriously interfere with the proper operation.

40 A further object of my invention is to protect this regulating device in a simple and efficient manner and at the same time permit of its ready adjustment by a proper person.

45 Reference is to be had to the accompanying drawings, which form a part of this specification, and in which similar reference characters indicate corresponding parts in the different views.

50 Figure 1 is a central, vertical section through a drinking fountain embodying my invention, and Fig. 2 is a central, vertical section through another form which my invention may assume.

In the specific form shown in Fig. 1, I 55 employ a cast metal body portion 10, having an upwardly projecting nozzle 11, a valve chamber 12 and a lower supporting coupling 13. The coupling may be of any form desired to adapt it for connection to a 60 supply pipe 14. The valve chamber is di- 65 vided by a partition 15 having a port there- through and a valve seat 16 for a puppet valve 17. The valve seat lies in a substan- 70 tially vertical plane, and the valve moves in a horizontal direction. It is normally held to its seat by a spring 18 disposed be- 75 tween the valve and a removal cap 19 on the high pressure side of the valve. The valve stem 20 is supported and guided in a lug 21 on the side of the valve casing, and within this lug is a suitable packing gland 22. It will be noted that when the valve is closed there will be no water pressure against this packing gland and, therefore, 75 no liability of leakage around the valve stem.

The valve is operated by a handle or arm 23 fulcrumed upon a pivot 24 at the outer end of the lug 21, and has its lower end nor- 80 mally in contact with or closely adjacent to the outer end of the valve stem. The up- 85 per end 26 of the arm or lever is disposed directly over the nozzle so as to form a pro- 90 tecting guard for the latter and normally prevent any one from placing his lips over 95 the nozzle. This guard 26 may be of any form desired, it only being essential that it effectively serve the purpose desired, that is, to protect the nozzle. The guard is prefer- 100 ably spaced a short distance from the nozzle, so as not to contact therewith, and is preferably of such shape as to permit it to be readily grasped in the hand to move it to one side in opening the valve. The ful- 105 crum of the lever arm 23 is very much nearer the lower end than the upper end, so that the guard 26 may be swung through a large arc in opening the valve. The valve is normally closed, and the guard is nor- mally over the nozzle, as shown in the draw- 110 ing, but by swinging the guard to one side, the valve will be opened and the water will flow before a person can place his lips over the nozzle. It is not essential that the par- 115 ticular valve or particular valve-operating mechanism shown in Fig. 1 be employed, as other means may be designed for accom-

plishing the same object. The particular form shown in Fig. 1 may be very inexpensively manufactured, as the main body is formed of a single casting and the forming 5 of the threads for the cap 19, the grinding of the valve seat 16 and the boring of the passage for the valve stem may all be done on a turret lathe without changing the position of the casting.

10 After the water passes the valve 17, it may flow upwardly into the nozzle 11 and out through an opening 27 in the top wall of the nozzle. The water is ordinarily delivered under rather high pressure, and it 15 is desired that the flow be uniform and comparatively slow, irrespective of the extent to which the valve 17 is opened. To secure this regulation, I form the nozzle 11 with an air chamber 28 and a perforated tube 29 extending inwardly and downwardly from the opening 27. This tube has a lower end wall 30 normally spaced a short distance from a seat 31 between the nozzle proper and the valve chamber. This inner 20 end wall has a transverse slot therein, so that by extending a screw driver through the tube into engagement with this inner end and rotating the tube, the latter may be moved longitudinally to bring it closer 25 to or farther away from this seat and thus regulate the flow. The regulating device is thus concealed and is unaccessible save to a person familiar with the construction and having a screw driver or other instrument 30 capable of insertion through the tube. The tube is shown as being adjustable by reason of its threaded connections with the wall of the nozzle. Instead of forming the tube in this manner, I might employ a tube 32 as 35 shown in Fig. 2, which is rigid with the nozzle. In this form, the inner end wall 33 constitutes a plug threaded in the tube, so that by inserting the screw driver through the tube, the inner end alone may be rotated 40 and adjusted relatively to the seat. The flow might also be regulated by adjusting this inner wall or plug 33 upwardly so as to 45 cover or partially cover some of the perforations in the tube.

50 In the form shown in Fig. 2, I employ a turning plug 34 in place of the puppet valve 17 shown in Fig. 1. This turning plug is provided with a handle 35 extending upwardly beside the nozzle and terminated in 55 a guard 36 disposed above the nozzle. With the valve closed, a person cannot place his lips to the nozzle, but the act of turning on the water serves to open the valve.

It is evident that other devices might be 60 designed to operate in accordance with the principles of my invention, for instance, the valve might move lengthwise of the valve chamber and the guard be in the form of a sleeve telescoping with the nozzle and movable downwardly to expose the nozzle and

open the valve. Instead of this, the nozzle might be vertically movable out of the sleeve to expose the nozzle and open the valve.

The total area of all of the openings in the tube 29 is less than the area of the outlet from the tube, so that these openings may be utilized as the means for reducing the pressure of the water. The tube and the bottom of the tube may be made non-adjustable and the perforations increased in 70 number from a minimum to give the desired flow.

Having thus described my invention what I claim as new and desire to secure by Letters Patent is:

1. A drinking fountain having an upwardly extending substantially rigidly mounted nozzle, a valve for controlling the flow therefrom, a guard spaced from the outlet of said nozzle and normally in alignment with said nozzle to prevent a person from placing the mouth over said nozzle, said guard being movable laterally out of said position for opening said valve and permitting the flow of water and means independent of said valve and operable through the outlet of said nozzle for restricting the flow.

2. In a drinking fountain, the combination of a nozzle, a puppet valve movable transversely thereof for controlling the flow therethrough and a protecting guard operatively connected to said valve and normally preventing a person from placing the mouth over the nozzle.

3. A drinking fountain, including a cast 100 metal body, including a valve chamber and an upwardly extending nozzle, a valve within said valve chamber, a spring for normally holding said valve in closed position, and a lever fulcrumed on said body and having one end operatively connected to said valve and the other end normally disposed directly above said nozzle to constitute a protecting guard therefor.

4. In a drinking fountain, the combination 110 of a water chamber having a water inlet and an outlet, a perforated outlet tube projecting into said chamber from said outlet, and having an open upper end, and a closed inner end, the space within said chamber 115 above the perforations in the tubing constituting an air chamber, and said inner end being adapted for rotation by a tool inserted through said tube to regulate the flow of water through the tube.

5. A drinking fountain, including a nozzle, a valve movable transversely thereof for controlling the flow therethrough and a protecting guard operatively connected to said valve and normally preventing a person from placing the mouth over the nozzle.

6. In a drinking fountain, the combination of a nozzle including a water chamber having an outlet at the top thereof, and a dome-shaped wall curving outwardly and 120

downwardly from said outlet, a delivery tube projecting into said chamber and removable through said outlet and adjustable to control the flow through said tube, a valve 5 normally preventing the flow through said tube and means for operating said valve.

7. A drinking fountain, including a water chamber having an upper portion constituting a substantially hemispherical dome with 10 an outlet at the top thereof, a perforated outlet tube projecting into said chamber from the top thereof, and having an open upper end substantially flush with said top and a closed inner end, said tube being end- 15 wise adjustable to control the flow therethrough.

8. In a drinking fountain, the combination of a water chamber having a water inlet and an outlet, a perforated outlet tube projecting into said chamber from said outlet and having an open upper end substantially flush with said top wall, and a closed inner end and said inner end being adapted for rotation by a tool inserted through said tube 20

to regulate the flow of water through said tube. 25

9. In a drinking fountain, a cast metal body having a nozzle chamber terminating in a substantially hemispherical dome with an outlet at the top thereof, a valve chamber, a passage connecting said chambers, a valve within said valve chamber, a delivery tube extending down into said nozzle from the outlet thereof, and having an open end substantially flush with the outer surface of 30 said nozzle chamber, and a closed inner end movable toward and from said port to control the flow from said valve chamber to said nozzle chamber independently of the 35 action of said valve. 40

In testimony whereof I have signed my name to this specification in the presence of two subscribing witnesses.

WILLIAM BRUCE KNAPP.
